UNITED STATES PATENT OFFICE.

JAMES TOTHAM, OF NEW HAVEN, CONNECTICUT.

DESIGN FOR A SLAB-SUPPORT.

SPECIFICATION forming part of Design No. 23,334, dated June 5, 1894.

Application filed May 11, 1894. Serial No. 510,947. Term of patent 7 years.

To all whom it may concern:

Be it known that I, JAMES TOTHAM, a citizen of the United States, residing at New Haven, in the county of New Haven and State of Connecticut, have invented and produced a new and original Design for Slab-Supports, of which the following is a specification, reference being had to the accompanying drawings, forming a part thereof.

10 In the drawings, Figure 1 is a view in side elevation of my slab support. Fig. 2 is a plane view of the angle rest *a*.

The leading features of my design consist in the angle rest *a*, terminating at its lower extremity in the octagonal and rounded ornament *a'* the ornamental bracket *b*, the octagonal and rounded ornament *b'* the octagonal angle piece *c*—*c*, supported on the fluted col-

umn *d*, which terminates at its lower extremity in the rounded, tapering and beaded post *e*—*e* which is supported on the claw foot *f*, grasping the ball *g*.

What I claim is—

The design for a slab support herein described, the same comprising the angle piece *a* terminating in the octagonal and rounded ornament *a'* the ornamental bracket *b*, the octagonal angle piece *c*, supported on the fluted column *d*, the rounded, tapering and beaded post *e*—*e* the claw foot *f*, and ball *g*, substantially as described and shown in the accompanying drawings.

JAMES TOTHAM.
